UNITED STATES PATENT OFFICE

OTTO JOHANN ABEREGG, OF BERN, SWITZERLAND.

SPEED-RECORDER.

1,073,555.

Specification of Letters Patent. Patented Sept. 16, 1913.

Application filed May 7, 1907. Serial No. 372,356.

To all whom it may concern:

Be it known that I, OTTO JOHANN ABEREGG, a citizen of the Confederation of Switzerland, residing at Bern, in the Canton of Bern and said Confederation, have invented certain new and useful Improvements in Speed-Recorders, of which the following is a specification, reference being had to the accompanying drawings.

10 My invention relates to improvements in speed recorders; and an object of my invention is to provide means for making a record, upon a strip of paper, of the speed and the time of the day, so that the speed 15 at any given time may be read from the record.

In the drawings illustrating the principle 20 of my invention and the best mode now known to me of applying that principle, Figure 1 is a section on the line A—B of Fig. 2; Fig. 2 is a side elevation part of the casing being broken away; and Fig. 3 shows a strip of paper bearing a record of speed and time as made by my new speed 25 recorder. Fig. 4 is a diagrammatic view, illustrating the combined mechanism.

Fastened upon the case 1 is a housing 2 in which is mounted a clockwork mechanism having an hour-shaft 30 and adapted 30 to be wound up by turning the milled head 3. Over the dial plate 4 move the hour-hand 5 and the minute-hand 6 of this clockwork mechanism. The dial-plate 4 is mounted upon the wall 13 from which project two studs 12, into longitudinally-extending, straight slots 11 formed one on each side of the enlarged upper end or head of the actuator-arm 8. The enlarged upper end or head of the actuator-arm 8 is also provided, as shown in the drawing, with a central, longitudinally-extending slot, through which the hour-shaft 30 projects, and by which the necessary freedom of movement of the arm 8, without interference with said hour-shaft, is insured. Upon 45 the hour-shaft 30 is mounted a heart-shaped cam 7 which is adapted to rub against the cam-rollers 14 carried by the head of the actuator-arm 8. It will be obvious that by 50 the rotation of the heart-shaped cam 7, the actuator-arm will be moved back and forth. The actuator-arm is guided by the walls of the opening 9 in the casing 1 and by the guide-plate 10 and by the pins 12, 12 projecting into the slots 11, 11. Mounted free

to rotate near the center of the case 1 is a sector 17 having a series of teeth 16 which mesh with the teeth 15 upon the lower end of the actuator-arm 8 and another series of teeth 18 which mesh with the teeth 19, 60 formed upon the upper end of the time-recording bar 21, the lower end of which is provided with a stylus or marker 20. By means of the toothed sector 17, the reciprocating motion of the actuator-arm 8 is 65 transmitted to the time-recording bar 21; and the actuating parts are so arranged that the movement of the marker 20 is uniform. In the lower portion of the case 1 is mounted a plate 23 having an opening 22 through 70 which is exposed a strip of paper 24. Upon the latter is ruled lines equidistant apart. The movement of the time-recording bar 21 is such that the marker moves across the exposed portion of the strip of paper 24 in 75 one direction in six hours and in the opposite direction in the following six hours. Hence the distance between the ruled lines on the strip of paper 24 may be taken to represent a period of one hour. The strip 80 of paper 24 is moved lengthwise by any suitable apparatus; as, for example, the apparatus described in the Swiss Patent, No. 27,946, granted to Arnold Werthmüller. For example, as shown in Fig. 4, a drum A 85 is illustrated that is mounted on a shaft B and is continuously driven through suitable gearing C from any source of power. The movement of the strip of paper 24 is made uniform by this apparatus and consequently the line drawn by the marker 20 will be a straight line, the motion of the time-recording bar 21 being uniform, as 90 already explained. In Fig. 3 is shown a strip of paper which bears a record of speed and time as made by my new speed recorder. The irregular line 25 is the speed line and is made by the speed-recording bar 40, which may be taken as representing 95 conventionally the speed-recording mechanism. The latter may be of the type shown and described in the Swiss Patent, No. 27,946, above referred to. The speed recording mechanism is illustrated in a diagrammatic manner in Fig. 4, and follows 100 the structure disclosed in the said Swiss patent. It is designated generally by the reference numeral D. The lowermost of the ruled lines on the strip of paper 24 is taken 105 to represent six o'clock a. m. and six o'clock 110

p. m. and the uppermost line will represent twelve o'clock noon and twelve o'clock midnight. The ordinates of the speed-curve measured from the lowermost line of the strip perpendicularly thereto giving the speeds at the times indicated by the hour-line 26.

In the particular case illustrated by the strip shown in Fig. 3, the start was made at 10 6:30 o'clock. Shortly before seven o'clock a stop was made and, as will be seen by the length of the straight part *a* of the speed curve and the corresponding part of the hour line, the trip was continued after a 15 delay of five minutes. Shortly after seven o'clock another stop was made and as is shown by the straight part *b* of the speed curve and the corresponding part of the hour line, this stop lasted fifteen minutes. 20 At 7:30 o'clock a. m. the automobile was stopped for a third time and did not start until a quarter past ten o'clock a. m. As is described in Swiss Patent, No. 27,946, the speed recording mechanism is always maintained wound up during the running of the automobile and after the automobile is brought to a stop the speed recording mechanism runs down within fifteen minutes from the time the stop is made. The 25 straight part *b*¹ shows that the speed-recording mechanism ran down but that the clockwork mechanism continued in motion, making this straight part *b*¹ of the hour line 26. The straight part *c* together with the corresponding portion of the hour line indicates that the stop lasted from 7:30 o'clock a. m. to quarter past ten o'clock a. m. as has been previously stated. The next stop was made at about 10:30 o'clock a. m. and lasted until 30 five o'clock p. m., as is plainly shown by the last straight part of the speed-curve and the corresponding part of the hour-line 26. The part *b*² of the hour-line shows that the clockwork mechanism continued in opera-

tion after the speed-recording mechanism 45 had run down.

From the foregoing description in connection with the drawings, it will be seen that my new speed recorder will be of great value in case of a dispute as to the speed 50 maintained by the machine at any given time, as where the police authorities say that the speed was at a given time in excess of that allowed by the law.

I claim:

1. In a speed-recorder, a time-recording bar; a clockwork-operated shaft; a cam carried by said shaft; an actuator-arm controlled by said cam, and having an enlarged head provided with a central, longitudinally-extending slot, through which said clockwork-operated shaft projects, and with two longitudinally-extending straight slots; stationary guiding-pins projecting through said two straight slots; cam-rollers carried 60 by said head and engaged by said cam, to move said actuator-arm; and an operative connection between said actuator-arm and said time-recording bar, whereby movement is transmitted from said actuator-arm to 65 said time-recording bar.

2. In a speed-recorder, a time-recording bar; a clockwork-operated shaft; a cam carried by said shaft; an actuator-arm controlled by said cam, and having an enlarged 70 head provided with a central, longitudinally-extending slot, through which said clockwork-operated shaft projects; cam-rollers carried by said head and engaged by said cam, to move said actuator-arm; and an operative connection between said actuator-arm and said time-recording bar, whereby movement is transmitted from said 75 actuator-arm to said time recording bar.

OTTO JOHANN ABEREGG.
